DESIGN FOR A COOKING STOVE

Herbert J. Moon, Granite City, Ill., assignor to National Enameling & Stamping Company,
Milwaukee, Wis., a corporation of New Jersey

Application April 24, 1941, Serial No. 100,608

Term of patent 14 years

To all whom it may concern:

Be it known that I, Herbert J. Moon, a citizen of the United States, residing at Granite City, in the county of Madison and State of Illinois, have invented a new, original, and ornamental Design for Cooking Stove, of which the following is a specification, reference being had to the accompanying drawing, forming part thereof.

The figure is a perspective view showing the front, top, and one side of a cooking stove illustrating my new design.

The side not shown and the back are plain.

I claim:

The ornamental design for a cooking stove, as shown and described.

HERBERT J. MOON.
